UNITED STATES PATENT OFFICE

123,675

DESIGN FOR A COMBINED POCKET COIN HOLDER AND ATTACHING MEANS THERE- FOR

John M. Jacobi, New York, N. Y.

Application September 17, 1940, Serial No. 95,133

Term of patent 7 years

To all whom it may concern:

Be it known that I, John M. Jacobi, a citizen of the German Reich, residing in the county of New York, city and State of New York, have invented a new, original, and ornamental Design for a Combined Pocket Coin Holder and Attaching Means Therefor, of which the following is a specification, reference being made to the accompanying drawing, forming a part thereof.

Fig. 1 is an elevational view of one side of a combined pocket coin holder and attaching means therefor, showing my new design;

Fig. 2 is a top plan view thereof; and

Fig. 3 is an elevational view showing the other side of the pocket coin holder; the attaching means shown in Fig. 1, being omitted in Figs. 2 and 3 for convenience of illustration.

I claim:

The ornamental design for a combined pocket coin holder and attaching means therefor, substantially as shown.

JOHN M. JACOBI.
